UNITED STATES PATENT OFFICE.

HENRY N. NEIREITER, OF DECATUR, INDIANA.

TILE-DRAIN INLET.

No. 902,104.

Specification of Letters Patent.

Patented Oct. 27, 1908.

Application filed April 27, 1908. Serial No. 429,325.

To all whom it may concern:

Be it known that I, HENRY N. NEIREITER, a citizen of the United States, residing at Decatur, in the county of Adams, in the 5 State of Indiana, have invented certain new and useful Improvements in Tile-Drain Inlets; and I do hereby declare that the following is a full, clear, and exact description of the invention, which will enable others 10 skilled in the art to which it appertains to make and use the same; reference being had to the accompanying drawings, which form part of this specification.

My invention relates to improvements in 15 tile-drain inlets for surface water.

The object of my present invention is to provide a comparatively cheap, simple, durable and convenient inlet for running surface water to tile drains, specially designed for 20 use upon farms, public highways, railway right of ways, and the like, and adapted to freely admit the surface water without danger of becoming clogged by drift wood, or freshets, interfered with by stock, or destroyed by the disintegrating effects of the 25 elements, as is the case with the ordinary sink-basin which is built of brick.

My invention consists of a metallic cylindrical conduit which is formed of longitudinal 20 interlocking sections, which can be readily assembled or disunited for repair without the aid of mechanical skill, and each of which is provided with a series of peripheral inlet perforations adapted to freely admit surface 35 water but which will exclude drift-wood or other obstructions, the said interlocking sections being covered at their outer end by a detachable perforated cap.

The principal novel feature of my invention 40 resides in the construction and arrangement by which the cylindrical inlet conduit is formed of interlocking and detachable longitudinal sections which can readily be assembled or detached for repairs.

Similar reference numerals indicate like 45 parts throughout the several views in which

Figure 1 is a view in elevation of my invention partly broken away and in position upon a section of drain-tile broken away in part to 50 show the manner of mounting my invention in position thereon. Fig. 2 is a plan view of my invention showing the arrangement of the means for uniting the component sections thereof. Fig. 3 is a detail inside view of one 55 of the component sections. Fig. 4 is a per-

spective view of the cap for closing the opening of the inlet.

My invention consists of a cylindrical drain inlet 1 having an offset flange 2 on its lower end adapted to snugly fit about a 60 proper boss or flange 3 of an inlet opening 4 in one of the tiles 5 of a proper tile drain.

When desired, as where the depth of the tile drain from the surface requires it, a plurality of the inlets 1 may be employed and united 65 endwise in the usual manner by the overlapping flange 2. The inlet 1 is formed of a plurality, preferably three, longitudinal sections 6 of identical construction, and provided upon their lower end with a flange 7 which 70 when united form the encircling flange 2 adapted to snugly fit over the adjacent end of the companion part 3 of the opening 4, as shown in Fig. 1. Each longitudinal metal section 6 is also provided with a series of lateral perforations 8 of any desired contour, 75 preferably circular, and of proper size to freely admit the surface water, and too small to admit fine drift wood or like obstructions. These sections 6 are also provided with bolt 80 openings 9, upon one side thereof, one near each end thereof, Fig. 3, and are provided upon the other side with correspondingly arranged off-set and laterally extended lugs 10 having a bolt opening 11 adapted to register 85 with the corresponding bolt opening 9 of the adjacent section 6. These sections 6 are rigidly and snugly secured together in one cylindrical section by means of proper bolts 12. The upper inlet section 1 is closed at its upper 90 end by a circular perforated cap 13 having a pendent peripheral flange 14 adapted to fit snugly within the top of the section 1 and form a locked engagement therewith. When one or more duplicates of the section 1 is used 95 it may have its lower end made with the flange 2 if desired which is fitted loosely over the flange or boss 3, and then rigidly secured in position by cement, or other proper manner.

The flange 2 is preferably provided with lateral perforations 15, as shown so that the inlet section can be more firmly secured in position, by allowing the cement to fill these 100 perforations.

It is obvious that by means of my improved construction the longitudinal metal sections 6 when taken apart can be compactly packed for storage or transportation, and as the weight of each section 6 is but one- 110

third that of an entire inlet section 1, they can be more readily and conveniently handled. It is also obvious that any unskilled operator can readily assemble the sections 6 5 and secure them in their operative position on the boss 3 or upon any suitable tile drain opening by means of cement, after which the metallic cap 13 cannot be displaced laterally or in any other manner without first lifting it 10 up until the retaining flange 14 clears the upper edge of the inlet section 1, whereby it is secure against derangement by stock or other ordinary incidents of service. While this is the preferable construction of the cap, it may 15 be made to interlock with the upper end of the section 1 in any other proper manner.

In case of breakage of one of the sections 6, which project slightly above the surface, by a striking contact with farming machinery and 20 the like, such section can readily be detached and replaced by first removing the bolts 12, thereby avoiding the expense of replacing an entire new inlet section.

While but one inlet cylindrical section may 25 be used where the drain is shallow or where the inlet section is of sufficient length, a plurality of the inlet sections should be used.

Having thus described my invention and the manner of employing the same, what I 30 desire to secure by Letters Patent is:

1. A tile drain inlet consisting of a plurality of curved longitudinal sections having a series of lateral perforations, and provided with means for detachably uniting the sections into an open ended cylindrical conduit 35 and an apertured removable cap adapted to close the upper end of the conduit.

2. An inlet for tile drains consisting of a cylindrical conduit formed of a plurality of curved longitudinal sections laterally apertured and provided with means for rigidly uniting the sections, and a removable cap adapted to close the upper end of the conduit. 40

3. A cylindrical inlet for tile drains comprising a plurality of perforated longitudinal sections provided at one edge thereof with apertured off set lugs, and having at their other edge lateral openings; means for securing the lugs of one section to the openings 50 of the adjacent section; and a removable perforated cap adapted to close the upper end of the said inlet. 45

Signed by me at Decatur, Adams county, State of Indiana, this 25th day of April, A. 55 D. 1908.

HENRY N. NEIREITER.
